UNITED STATES PATENT OFFICE

2,563,449

HEATER STRUCTURE

John M. Aufiero, Plandome, N. Y., assignor to
E. A. Laboratories, Inc., Brooklyn, N. Y., a corporation of New York

Application July 15, 1949, Serial No. 104,973

1 Claim. (Cl. 219—39)

1

This invention relates to a structurally and functionally improved heater assembly and especially an apparatus which is capable of being readily transported; such apparatus depending for its heat source and operation upon electric current.

It is a primary object of the invention to furnish a heater structure which will be alternative to and in certain aspects presents improvements over the structures disclosed in my prior applications for United States Letters Patent filed on May 12, 1948, under Serial Numbers 26,492 and 26,493, now Patents No. 2,504,785 and No. 2,506,408, respectively.

A further object resides in the provision of a structure in which heat transfer will occur not alone due to the flow of air past heated surfaces such as coils, but also due to radiant heat. Therefore, the user will be subjected to the pleasant sensation of a warm air flow and will additionally receive the benefit of heat rays as directed towards him; the latter additionally creating the psychology of a warming effect.

Still another object is that of furnishing an apparatus type in which the wire will be properly housed and protected so that an extremely neat and commercially desirable assembly is furnished.

Still another object is that of providing a design which will embody relatively few parts each individually simple and rugged in construction, such parts being capable of ready manufacture and assemblage and when so assembled operating over long periods of time with freedom from all difficulties.

With these and other objects in mind, reference is had to the attached sheet of drawings, illustrating one practical embodiment of the invention and in which:

Fig. 1 is a front view of the apparatus with certain of the parts broken away to disclose underlying structures;

Fig. 2 is a sectional side view taken along the lines 2—2 and in the direction of the arrows as indicated in Fig. 1, and;

Fig. 3 is an enlarged transverse sectional view of a portion of the assembly and taken along the lines 3—3 and in the direction of the arrows as indicated in Fig. 1.

In these views the numeral 5 indicates the base portion of the apparatus which may be provided with suitable supporting elements 6 and mounts by a pivot 7, a strap 8. The latter is conveniently of generally U-shape and mounts adjacent the ends of its arms pivot members 9 which are secured to a housing conveniently

supporting a handle 10 adjacent its upper end. The configuration of the several parts may be varied in numerous particulars. However, as shown, it is obvious that the supporting strip or bracket 8, may be axially rotated as desired with respect to base 5. Also, the housing may be tilted around a horizontal axis as defined by the elements 9 and may be clamped against movement by these elements. Additionally the entire apparatus may be transported by the handle 10.

As has been shown especially in Figs. 1 and 2, the housing is preferably of generally circular shape. It includes spaced walls 11 and 12. Brackets 14 may be coupled to extend from inner face of the latter wall and may be secured against movement with respect to each other. These brackets mount a motor 15; a cushioning strip 16 being conveniently interposed between the encircling portions of the brackets and the outer face of the motor casing. Grilles 13 may be disposed adjacent the forward and rear faces of the housing so that air may freely circulate therethrough. A fan 17 is mounted by the motor shaft to be driven thereby.

Supporting units 18 may extend outwardly from the motor casing and mount forwardly extending arms 19. The latter support a mounting 20 which at spaced points has secured to it refractory spools or elements 21 conveniently by means of screws or bolts 22. The latter provide support for a helical coil of resistance wire 23. As shown especially in Fig. 1, that coil may be disposed according to the configuration of a star, having any desirable number of arms.

As shown in detail in Fig. 3, a strip 24 is interposed between the spools 21 and the mounting 20. This strip should have an outline corresponding to the configuration of coil 23. As shown, it is preferably flat. Its forward face may be bright or polished so as to furnish a reflecting surface. As is apparent, the coil 23 may lie substantially midway between the edges of strip 24. It will be reflected in the face of this strip. Therefore, if the latter is incandescent the resultant effect will be magnified or duplicated to an observer in advance of the heater.

Current-supplying lead 25 extends from a point beyond the housing through an opening in the same and into the space between walls 11 and 12. These leads project through an opening preferably in the inner wall 12 and are connected to the resistance 23 and the motor 15. Also, they are connected to a switch 26. The actuator for the

latter may extend through the outer wall 11. In this manner it is apparent that the leads are adequately housed and protected and that a neat appearance is presented regardless of the manner in which the housing is tilted or turned with respect to its face.

As will be apparent the several parts may be adjusted and secured to each other if a pivot 7 and elements such as 9 are employed. Thereafter, switch 26 may be actuated. According to one such actuation and as described in my earlier application heretofore referred to motor 15 will operate at full speed to correspondingly drive the fan and assure of passage and distribution of a maximum amount of air through the housing. Under these circumstances the resistance will be inoperative, or substantially so and the air flow will be used for ventilation or cooling. According to another positioning of the switch part the motor and the resistance 23 will be in series with each other.

Under these circumstances the motor will operate at substantially less speed and instead of distributing cool air will cause a relatively gentle flow of such air past the resistance which is now highly heated. Under such flow the air will be warmed by flowing over and through the convolutions of coil 23 and the parts adjacent thereto. In this connection, it will be observed that the resistance is spaced from and otherwise related to the strip 24 in a manner such that a baffle effect is created and the air flows over the edges of the strip and thence towards the coils. Therefore, a proper heat exchange will occur. Additionally, however, it is apparent that the glowing or incandescence of the resistance coil will be somewhat enhanced because of this baffling effect. A person in a position to be warmed by the heater or in other words, in front of the same will not alone be aware of the incandescence of the coil, but this effect will be magnified incident to the reflection of the incandescent image of the latter in the face of strip 24. Therefore, a psychological effect will be produced which is most pleasing; this being in addition to the rays which are radiated towards the observer particularly because of the preferably reflecting nature of strip 24.

As shown, the current-supplying leads are connected to the resistance by extending to dielectric blocks 27. The latter are supported by certain of the arms 19. Terminals 28 are carried by the blocks and serve to connect the leads with the resistance and motor. In this manner, an extremely compact and safe assembly is furnished.

Thus among others, the several objects of the

invention as specifically aforesaid are achieved. Obviously, numerous changes in construction and rearrangement of the parts might be resorted to without departing from the spirit of the invention as defined by the claim.

I claim:

A heater including in combination a shroud forming a circular casing, a motor driven fan positioned within said shroud to produce a flow of air therethrough; a bracket support within said shroud supporting said fan; a narrow elongated flat strip mounted on said supporting bracket perpendicular to the axis of said shroud and the axis of rotation of said fan; a flat reflecting face on the surface of said strip adjacent said fan; insulating supports mounted on said strip projecting toward said fan perpendicular to the longitudinal dimension of said strip, mounts on said insulating supports, an incandescent electrical resistance having a diameter at least one-half the width of said reflecting face and spaced from said reflecting face on said mounts in advance of the reflecting strip between the latter and the fan, said electrical resistance positioned in line with the dimension of said insulating strip between said strip and the fan, narrow flat edges of said reflecting face perpendicular to the axis of said shroud and the axis of rotation of said fan extending in said perpendicular plane to provide said reflecting face with a width less than twice the diameter of said resistance whereby air in its movement through the shroud under the impulse of the fan flows outward around the edges of the flat strip and contacts the resistance on flowing inward across the reflecting surface through the spacing of the resistance from the flat strip from which resistance the heated air is projected by the fan blades out of the shroud while the incandescence of the electrical resistance is visibly reflected in the narrow longitudinal edges of the reflecting face.

JOHN M. AUFTERO.
